DESIGN FOR A BICYCLE AND AUTOMOBILE JEWEL AND SUPPORT

Harry Golden, New York, N. Y.

Application April 25, 1947, Serial No. 138,609

Term of patent 7 years

(CL. D90—1)

To all whom it may concern:

Be it known that I, Harry Golden, a citizen of the United States of America, residing at New York, county of New York and State of New York, have invented a new, original, and ornamental Design for Bicycle and Automobile Jewel and Support, of which the following is a specification, reference being had to the accompanying drawing, forming a part thereof.

Figure 1 is a front elevational view of a bicycle and automobile jewel and support embodying my new design;

Figure 2 is a side elevational view thereof; and
Figure 3 is a rear elevational view of the same.

I claim:

The ornamental design for a bicycle and automobile jewel and support, as shown.

HARRY GOLDEN.
